UNITED STATES PATENT OFFICE.

JAMES SIDNEY ROARK, OF AMERICUS, GEORGIA, ASSIGNOR OF ONE-HALF
TO RICHIE T. HARPER, OF SAME PLACE.

BLOWER FOR GRATES.

SPECIFICATION forming part of Letters Patent No. 653,365, dated July 10, 1900.

Application filed February 24, 1900. Serial No. 6,342. (No model.)

To all whom it may concern:

Be it known that I, JAMES SIDNEY ROARK, a citizen of the United States, residing at Americus, in the county of Sumter and State 5 of Georgia, have invented certain new and useful Improvements in Blowers for Grates, of which the following is a specification, reference being had therein to the accompanying drawings.

10 This invention has reference to open-grate fireplaces, the object being to provide an attachment to serve as a blower, by the use of which the draft can be regulated and the gases formed from the coal can be wholly consumed.

15 To this end the invention consists in an open-grate fireplace provided with a frame extending across the top and at either side of the fireplace and having a receptacle or pocket in its top portion.

20 It also consists in a collapsible screen made up of a plural number of slats or plates partially overlapping one another and loosely united by slots and rivets, the screen being intended to fold up when not in use so as to

25 be received in the aforesaid pocket, where it is retained by a hinged plate or equivalent means, another hinged plate depending from the lower end of the screen serving to close the pocket.

30 The invention further consists in certain details of construction whereby the improved attachment may be adapted to answer the purpose of a summer front, with the two-fold advantage of being an ornament and an economy.

35 Reference is to be had to the accompanying drawings, forming part of this specification, in which similar letters of reference indicate corresponding parts in the several views.

40 Figure 1 is a front elevation of an open-grate fireplace having my attachment, the screen being folded back into the pocket. Fig. 2 is a central vertical section through the same, the screen being shown here down to 45 serve its purpose as a blower. Fig. 3 is a detail of the screen, showing the manner of uniting the slats or plates. Fig. 4 is a cross-section through the receptacle or pocket closed, the screen appearing in its folded state; and 50 Fig. 5 is a rear face view of the screen, showing the slots and rivets.

A denotes the usual fireplace, and B the grate, provided at its front with a shelf b. With this as a basis the invention may be defined as comprising a frame C, which is preferably hollow and constructed of cast metal, having the pedestals c c and the curved side and top members or moldings d d', provided with any suitable ornament or design—for instance, with the bead or column d''. The top 60 member d' is formed as a receptacle or pocket d'', having preferably inclined bottom d''' and front opening d'', the latter being of rectangular shape and extending longitudinally midway thereof. 65

The blower comprises a collapsible screen D, made up of a plurality of metal slats or plates e. These are made with double walls either by doubling the metal back upon itself or, as shown in the present instance, by making the slats in two pieces, as clearly illustrated in the detail Fig. 3. Here the slat is shown as consisting of a front member e, with its longitudinal edges turned back, forming flanges e', which embrace and retain a flanged 70 plate e''. This construction is advantageous in affording space for heat radiation, thus obviating blistering or other possible injury to the polish or other finish with which the screen will generally be provided due to the 75 intense heat to which it must necessarily be exposed when in use.

The slats may be yieldingly united in any suitable manner; but I prefer to do this by providing the back member e'' with transverse 80 slots f, generally two in number, one at either end thereof, and with rivets g, contiguous said slots, adapted to slide in corresponding slots in the next adjacent slat, the slots being arranged in tiers of four, receding toward 85 the middle of the screen. By this construction the slats can readily be folded one upon the other. The uppermost slat has a hinge h, by which it is connected to a plate i, which in turn is hinged at j to the upper part of inclined bottom d''. Another plate k is hinged 90 to the lower part of the screen at k' and has a pair of rings l to facilitate folding or unfolding the screen. This plate serves admirably as a closure for the pocket when the 95 screen is drawn up out of use and will be also provided with a bead or column d'' or other 100

appropriate design to coincide with the ornament on the lateral members *d* of the frame. To facilitate the placing of the plate *k* in this position, two spring-guides *m m* are provided 5 on the upper member *d'*, which bear against either end of the plate.

It will be apparent that with my improved blower the draft can be regulated at will as the screen can be adjusted to any position. 10 The attachment can also be used as a summer front, and viewing the improvement from a standpoint of economy the advantage of such an arrangement is obvious.

Having thus described my invention, I 15 claim—

1. A blower such as described, consisting of a collapsible screen formed of a plural number of partially-overlapping double slats or back-lined plates, said plates having each 20 rivets at either end thereof, and transverse slots mediate said rivets, adapted to engage corresponding slots and rivets, respectively, in the next adjacent plate, and a supporting-frame having a pocket with a closed bottom, 25 substantially as described.

2. The combination with a frame having a pocket in the top thereof open toward the front, of a blower consisting of a collapsible screen formed of a plural number of metal 30 slats or plates, said plates having each rivets at either end and transverse slots mediate said rivets, adapted to engage corresponding slots and rivets, respectively, in the next adjacent plate, said screen having a hinged connection in said pocket and a depending plate 35

to close said pocket when the screen is not in use, substantially as described.

3. The combination with an open-grate fireplace, of a mantle attachment or frame, comprising top and lateral members, the top 40 member formed as a receptacle or pocket open toward the front and having an inclined bottom, of a blower consisting of a collapsible screen formed of a plural number of metal slats or plates having a front double-flanged 45 member and a back member embraced thereby, with a space between said plates for heat radiation, said back member having rivets substantially near its ends and transverse slots mediate said rivets adapted to engage 50 corresponding slots and rivets, respectively, in the next adjacent plate, a plate hinged to the upper of said slats and to near the rear of the pocket whereby the screen can be collapsed and folded back therein, and a hinged 55 plate depending from the lowermost slat, adapted to serve as a closure for the pocket, and a shelf or plate extending laterally across the front of the grate and against which the screen is adapted to abut when in its lowermost position for completely closing the fireplace save through the grate, substantially 60 as described.

In testimony whereof I affix my signature in presence of two witnesses.

JAMES SIDNEY ROARK.
